HIGH VACUUM ELECTRON TUBE

Christoph Edelmann, Vilshofen, Germany

Application February 3, 1927, Serial No. 165,542
In Germany February 5, 1926

2 Claims. (Cl. 250—27.5)

This invention relates to a high vacuum electron tube for wireless communications and the like composed of the usual anode, cathode and grid.

5 In customary structures of this type the anode is constituted by a more or less flat surface, usually in the form of a cylinder, and is therefore at all points equidistant from the cathode.

The anode current depends, aside from the 10 anode potential, on the spacing between the anode and the cathode, and, owing to the characteristics of the electron stream, particularly on the size of the anode surface. The anode current depends on the number of electrons which the anode 15 can simultaneously receive.

In prior structures, when it was desired to increase the anode surface, the spacing between the anode and cathode had to be increased, which in turn necessitated an increase in the anode potential.

According to the present invention, the anode surface is increased without increasing the spacing between the anode and the cathode and without increasing the anode potential. This is accomplished by providing steps or projections on the anode pointing in the direction of the cathode, said projections or steps being preferably of different lengths. In this manner the electron stream will be subdivided and distributed. The 30 appreciable increase of the anode surface thus

obtained will beneficially affect the harmful space charge.

The drawing represents schematically an exemplification of the invention in which—

a is the tube, *c* the cathode which, in the usual manner, is connected with a battery *f*. The anode *e* is provided with a plurality of projections *m* of different lengths pointing towards the cathode. The usual grid is indicated at *d*.

The operation is as follows: The electrons 65 emitted by the cathode are attracted by the projections *m* to points at varying distances from the anode, since the projections are of varying lengths. Owing to this the space charge will be better distributed than with an anode lacking 70 the projections of varying lengths.

What I claim is:—

1. An electron tube comprising an electron emitting body, a grid, and an anode having projections of different lengths for receiving electrons, thereby increasing the effective anode surface upon which electrons are received, said projections being directed toward the same body. 75

2. An electron tube comprising an electron emitting body, a grid, and an anode provided with 80 steps for receiving electrons, said steps being directed toward said body and enlarging the effective anode surface upon which electrons are received.
